UNITED STATES PATENT OFFICE

130,148

DESIGN FOR A BARREL

William I. Hanrahan, New York, N. Y., assignor to The Petroleum Iron Works Company of Ohio, Petroleum, Ohio, a corporation of Ohio

Application March 26, 1941, Serial No. 99,916

Term of patent 14 years

To all whom it may concern:

Be it known that I, William I. Hanrahan, a citizen of the United States, residing at New York, in the county of New York and State of New York, have invented a new, original, and ornamental Design for a Barrel, of which the following is a specification, reference being had to the accompanying drawing, forming part thereof, wherein

The dominant features of my design reside in the portions shown in full lines in the drawing.

I claim:

The ornamental design for a barrel, substantially as shown and described.

WILLIAM I. HANRAHAN.
